Patented Oct. 28, 1913.

UNITED STATES PATENT OFFICE.

EMIL GUSTAVE BOGUSCH, OF LLANO, TEXAS, ASSIGNOR OF ONE-HALF TO M. D. SLATOR,
OF LLANO, TEXAS.

INTERNAL-COMBUSTION ENGINE.

1,077,033.

Specification of Letters Patent. Patented Oct. 28, 1913.

Application filed April 30, 1913. Serial No. 764,559.

To all whom it may concern:

Be it known that I, EMIL GUSTAVE BOGUSCH, a citizen of the United States, and a resident of Llano, in the county of Llano and State of Texas, have invented an Improvement in Internal-Combustion Engines, of which the following is a specification.

My invention is an improvement in that class of explosive engines in which two hollow pistons are employed, one working slidably within the other and both connected with a triple crank shaft in such manner that they reciprocate simultaneously in opposite directions.

I have devised an improved construction, arrangement, and combination of parts whereby certain advantages are obtained.

The invention is hereinafter described with reference to the accompanying drawings in which—

Figure 1 is a central vertical section of the entire engine, showing the pistons in the position they occupy when the explosive mixture is ignited by a spark plug. Fig. 2 is a similar section showing the pistons separated from each other to near the limit of their strokes. Fig. 3 is a cross section taken at right angles to Figs. 1 and 2 and showing the pistons separated their fullest extent. Fig. 4 is a vertical section taken at right angles to the section shown in Fig. 3. Fig. 5 is a detail view illustrating a certain position of a valve.

The upper portion of the engine casing 1 is provided with spaces 2 for water-jacketing in the usual way, and the lower portion 3 of the casing is constructed to form a crank case.

The casing 1 has a lateral air-inlet port 4, and, on the opposite side, near the upper end of the piston, there is a narrow air-outlet port 5. The latter communicates with a by-pass 6 having a rotary two-way valve 7. The function and operation of these parts will be presently described.

Within the casing are two elongated hollow cylindrical pistons 8 and 9 arranged telescopically, that is to say, one being slidable within the other, and both are connected by pinions 10 and 11 with the cranks 10^a and 11^a of a rotary shaft journaled in the case 3. The outer piston 9 is provided near the top with a lateral port 13—see

Figs. 1 and 3—and near its lower enlarged end with a port 14—see Figs. 2, 3 and 4.

In the operation of the engine, the upper port 13 registers at each stroke of piston 9 with the by-pass 6, and the lower port 14 registers similarly with a lateral passage 15 in the casing 1 which serves for exhaust of burned or spent gases.

At a point nearly opposite the exhaust port 14, the outer piston 9 is provided with a port 16—see Figs. 1, 2 and 4, and such port is extended upward in the enlarged or thickened base portion of the piston, as indicated at 16^a, so as to communicate with a gas compressing chamber 17 formed between the abutment or shoulder 19 of the piston 9 and the corresponding shoulder 19^a of the casing 1. The latter is provided at 18 with a lateral port for admission of the ignitable mixture to the space 17.

At a point above the middle of the casing 1, a spark plug 20 is located and adapted to register with the port 13 of the outer piston 9 when the pistons are in the position shown in Fig. 1, in which instance the explosive mixture is compressed between their heads. 80

The general operation of the engine may now be understood.

When the pistons are in the position of nearest approximation, as in Fig. 1, the explosive mixture compressed between their heads is fired by the spark plug 20 and the pistons separate, as illustrated in Figs. 2 and 4. When the pistons are in the position shown in Fig. 1, the explosive mixture is admitted through port 18 to the annular space or chamber 17, and as the outer piston moves upward, the mixture is compressed between the shoulder or abutment 19 of the piston 9 and the shoulder 19^a of the casing 1, since such shoulders or abutments approach each other, as shown in Figs. 2 and 4. The previous charge compressed between the heads of the pistons, wherein the position indicated in Fig. 1, being ignited by the spark plug, the pistons separate and as 100 the inner piston 8 descends to the position shown in Fig. 2, the exhaust port 14 is uncovered and the burned gases escape. It

will be noted that at this instant, the lateral port 16 of the outer piston is not uncovered, 105 but in the further separation of the pistons, as indicated in Fig. 4, this occurs, and the gaseous mixture previously compressed in

the chamber 17 discharges into the outer piston at an upward angle, as indicated by dotted lines in Fig. 4.

In the further rotation of the crank shaft, 5 the exhaust 14 is closed so quickly that the gas mixture filling the chamber of the outer piston is confined and compressed until the port 13 of the outer piston again registers with the spark plug, as shown in Fig. 1, at 10 which time it is ignited.

The operation of the engine in respect to the air ports 4 and 5, by-pass 6, and valve 7 in connection with the pistons will now be briefly indicated. Assuming the valve 7 is 15 in the position shown in Figs. 1, 2 and 4, when the outer piston 9 is at its outer point as shown in Fig. 1, the lateral port 4 is entirely uncovered and air has free admission; but as the piston 9 ascends, such admission 20 is cut off and the charge of air taken in is compressed and at the same time port 13 in piston 9 registers with by-pass 6, as shown in Fig. 2, and the compressed air then discharges through the by-pass and the valve 25 into the space between the pistons 8 and 9, thus aiding in complete exhaust of the burned gases through the registering ports or passages 14 and 15. If, however, the valve 7 be manually adjusted, that is to say, 30 turned half around to the position shown in Fig. 5, it establishes communication between the lateral port 5 and the upper leg of the by-pass, so that at the next reciprocation of the piston 9, the charge of air 35 taken in at 4 is forced out through the ports 6 and 5 and may be utilized for expanding tires of autos or stored in a tank under compression, for subsequent use. Thus it

will be seen that this portion of the apparatus serves two purposes, namely, as an aid in the scavenging of the explosion chamber and practically as an air pump for special uses.

In practice, a check valve is provided in the air discharge pipe 5, and the same will be seated toward the valve 7 so as to prevent reflow of air forced past it.

I claim:

An internal-combustion engine comprising a casing provided with lateral ports for admission of the explosive mixture and for exhaust after explosion, said casing having also a spark plug and an abutment in its middle portion; two telescopic pistons and a crank shaft with which they are connected so as to reciprocate in opposite directions, the outer piston having an ignition opening in its upper portion and lateral ports in its lower portion for communication with the inlet and exhaust ports of the casing, the upper portion of the casing having a lateral air inlet and discharge, also a by-pass communicating with the discharge opening, and a rotary two-way valve arranged in said by-pass for controlling admission of compressed air into the space between the pistons for aiding in expulsion of burned gases or directing such air to the lateral discharge, the ignition opening in the outer piston being adapted in one position of said piston to register with the aforesaid by-pass, as described.

EMIL GUSTAVE BOGUSCH.
